United States Patent Office.

PAUL COUSIN AND PIERRE OURY, OF PARIS, FRANCE, ASSIGNORS, FOR ONE-THIRD, TO N. WASHAUER, OF NEW YORK CITY.

Letters Patent No. 97,607, dated December 7, 1869.

PROCESS FOR DECORATIVE OIL-PAINTING.

The Schedule referred to in these Letters Patent and making part of the same.

Be it known that we, PAUL COUSIN and PIERRE OURY, of the city of Paris, in the Empire of France, have invented certain new and useful Improvements in Decorative, Mural, Oleo-Chromo Oil-Painting, of which the following is a specification, the same having been patented by us in France, under date of April 19, 1869.

Nobody has succeeded, up to the present time, to apply, by machinery, the oil-painting on walls or panels for decorating the interior or exterior of buildings. This is the result we propose to obtain by the process which is the object of the present application for Letters Patent.

The name we give to our invention clearly shows its essential character, which consists in applying the process used in chromo-lithography to print designs in oil-colors, on an intermediate paper, from which the same can then be transferred by the process of decalcomanie.

Another specialty of our invention consists in the various means that we have devised for the preparation of the transfer-paper, of the colors to be transferred, and finally, of the paste required to cause the adherence of the decoration to the wall.

We will now give a description of our process, following, step by step, the various operations of which it consists.

We will take the process at its inception. Supposing, for instance, that some design or plan, in various colors, has been selected, and that it is desired to reproduce it in oil-colors one or more times upon a wall; in a word, that we wish to reproduce it in a mural painting.

We at first take some very thin, unsized paper, such as is generally used, and steep it, on one side only, in sizing.

The sizing employed is strained through very fine linen, and then heated by steam up to a temperature of from sixty to seventy degrees.

Its peculiar virtue is to be exempt from all kind of fermentation, and by means of the oily substance which it transfers to the paper, forms a varnish, which is water-proof, and which protects the paper from the action of all foreign substances.

This special sizing of the paper may be done by hand, or by means of a machine provided with a fine brush, under which the paper must be passed without stopping. The paper is then allowed to dry at an ordinary temperature.

A design, composed of several figures or symbols, has been previously made in one or more colors. From this design several plates or stones are engraved, a number equal to the various colors. The various operations are then carried on, only the order employed in chromo-lithography is reversed, that is to

say, that the bright colors are put on first, and the background forms the first coating.

We prepare our colors with the following materials:

We take No. 1 Almacica gum, No. 2 Sierra-Leone gum, and to this we add crude oil as a seccative. In order to render these substances agglutinal and oily, they must be heated up to 500° or 600°.

The color can only be mixed with linseed-oil when used for decoration, and never with essences; but for the ground-coating, the color must only be mixed with essences, and not with oil. After the color has been mixed, care must be taken to add No. 1 and No. 2; no matter what the preparation may be.

After the printing has been made on all the plates perfectly prepared, the paper is impregnated with the design, in all its colors, and is in readiness to be used for the transfer of the design to the walls or panels, and, in general, to all flat surfaces which it may be desired to decorate.

The wall or panel must be cleaned, and, if need be, moistened, and then the paper applied, after, however, having spread upon it a paste on the side of the ground-coating.

This paste is prepared from barley flour, and it is well to add a solution of alum, with a sprinkling of black pepper and camphor. These precautionary measures will have the effect of protecting the painting from insects and dampness.

In affixing to the wall the sheets of paper bearing the design, and the paste, its transparency will serve as a guide to attain precision in joining.

The appliance being terminated, the decalcomanie may be proceeded with at once, but it is better to allow it to dry during about ten hours.

The sheet of paper is dampened with a sponge, and becomes detached, and falls almost by itself, leaving all the painting on the wall, to which it is thus transferred with all the distinctness of outline, and all the brilliancy of color. Moreover, it adheres and is fixed to the wall with greater security than a painting by the brush.

If a varnished painting is desired, the varnish is afterward applied to the wall, or a coat of varnish is applied to the paper, before the same is printed in colors.

The engraved plates may be of metal, with the design in *basso* or *alto-reliero*, according to the nature of the painting desired.

The Almacica and Sierra-Leone gums are extracted from the same tree, (*Hymenaea courbaril*.)

Having thus described our invention,

What we claim, and desire to secure by Letters Patent, is—

1. The process, substantially as herein described,

of preparing paper, and applying thereto designs in oil-colors, and transferring the same to walls or other surfaces, as set forth.

2. The use of paper, when treated or prepared, as herein described, for the reception and transfer of designs in oil-colors, as set forth.

3. The use of Almacea, Sierra-Leone, or similar gums, when treated, substantially as herein described, and combined with oil-colors, for the purpose set forth.

4. The paper, with the designs printed thereon, and ready for transfer, as herein described, as a new article of manufacture for mural decoration.

PAUL COUSIN.

PIERRE OURY.
